SWINGING DRAWER CABINET

Wilbert E. Schauer, Milwaukee, Wis.

Application May 19, 1949, Serial No. 94,230

6 Claims. (Cl. 312—270)

1

This invention relates to a swinging drawer cabinet.

The primary object of the present invention is to provide a cabinet in which the several drawers and the base and cover are in marginal contact throughout the cabinet when the drawers are closed, thereby eliminating intervening partitions or dust stops and yet providing a fully dustproof construction, at the same time providing mechanically for clearance between any one of the drawers and the surfaces above and beneath it whenever such drawer is opened. In this way, each drawer is completely free as soon as swinging movement from its closed position is initiated and sticking is substantially eliminated.

Further objects of the invention include the provision of a novel and sturdy cabinet organization; the provision of simple and effective means for locking the several drawers; and the provision of a simple and effective way of providing metal bearing and cam surfaces and mounting these in drawers of otherwise non-metallic construction.

The invention will be more clearly apparent from the following disclosure of the invention with particular reference to the accompanying drawings in which:

Fig. 1 is a view in perspective showing a complete cabinet embodying the invention, one drawer thereof being swung to open position.

Fig. 2 is a fragmentary view of one of the drawers as it appears in inverted plan, portions of the drawer and contiguous parts being broken away to the section indicated at 2—2 in Fig. 3.

Fig. 3 is a fragmentary detail view through the cabinet and portions of two of the drawers thereof in vertical longitudinal section.

Fig. 4 is a fragmentary detail view through the cabinet in horizontal section in a plane showing one of the drawers in plan.

Fig. 5 is an enlarged fragmentary detail view taken in section on the line 5—5 of Fig. 4.

Fig. 6 is a fragmentary detail view taken in section on the line 6—6 of Fig. 5.

Fig. 7 is a fragmentary detail view in perspective showing in mutually separated positions the component parts of one of the drawers including the metal bearing and cam element incorporated therein.

Fig. 8 is a fragmentary detail view in perspective showing the upper portion of the cabinet with the top removed to expose the floating dust stop, the drawer therebeneath being partially open.

2

Fig. 9 is a fragmentary detail view in perspective showing a preferred bearing tube structure.

Fig. 10 is a view in transverse section through one of the locking pins to show a preferred means of mounting a spring anchorage thereon.

Fig. 11 is a view partially in side elevation and partially in axial section through the parts shown in Fig. 10.

Fig. 12 is an enlarged fragmentary detail view showing in side elevation two successive bearing sleeves mounted on the pintle and slightly separated for the better illustration of their cam surfaces.

15 My improved cabinet comprises a base 10 and a top 11 rigidly connected by a back which may comprise corner posts 12 and 13 and an intervening panel 15 (Figs. 1 and 4). While these parts are preferably made of wood, it will be understood that the invention is by no means limited to a wooden structure. The left front corner of the top, as viewed in Fig. 1, is unsupported, but the right front corner of the top is supported from the base by a pintle shaft

20 16 which, as best shown in Fig. 5, may desirably comprise a tube, anchored by means of screw 17 to a corner block 18 fixed in the base and similarly anchored by means of screw 19 to a corner block 20 fixed in the top 11. In order to minimize the weight of this shaft, I may use aluminum for the tube 16. While reference has been made to the location of the pintle 16 in the right front corner of the cabinet, it will, of course, be understood that this is merely by way of description of the particular embodiment illustrated, it being immaterial whether the drawers or trays pivot at the right or the left.

The bottom drawer 21 is desirably made fast upon the base 10 as a part thereof. It is fully exposed when the drawer or drawers immediately above it are swung out to one side. In the embodiment herein shown to exemplify the invention, there are three swinging drawers 22,

23 and 24, drawer 23 being shown open in Figs. 1 and 5 and drawer 24 being shown open in Fig. 8. Since the drawers are movable axially as well as angularly through means presently to be described, I provide a floating filler 25 which moves telescopically within the top 11 and keeps

45 50 closed the space between top 11 and the top drawer 24.

Assuming that the drawers are made of wood, the following is a convenient means of providing bearings therefor to enable them to pivot on the pintle 16.

3

Spanning the front righthand corner of each drawer (as viewed in Fig. 1) is a block such as that shown at 26 in the drawer 23 in Figs. 1, 5 and 6 and in drawer 22 in Fig. 7. A vertical kerf or channel 27 in the interior face of this block receives a cam-ended bearing tube 28, holding such tube snugly in the corner of the drawer as clearly shown in Fig. 6. One or more transverse arms 29 are carried by the sleeve 28 intermediate the end thereof. These arms may be 10 integral with the sleeve, this being a particularly desirable construction if the sleeve is made of sheet metal rolled into the form of a split tube from the margins of which the arms project as shown in Figs. 6 and 9. However the arms are 15 fastened to the sleeve, each is desirably received into a cross slot 30 in the wooden block, thereby constraining the sleeve 28 and the drawer 23 to rotate as a unit upon the pintle shaft 16 which provides a bearing for such rotation.

The upper and lower ends of each of the several sleeves are correspondingly beveled at any suitable angle, preferably about 35° to the horizontal, as shown at 31 and 32 (see Fig. 12). These cam surfaces may, if desired, terminate 25 near a transverse axial and diametrical plane. At the other side of such plane, each of the sleeves is nearly horizontal but, to preclude any wedging action as between the several sleeves which would increase their lateral thrust upon the pintle shaft 16, it is preferred that the top surface 33 of one sleeve and the complementary lower surface 330 of the next sleeve have a slight 30 downward pitch away from the set plane as indicated by the broken lines in Fig. 12 so that, in the closed position of the drawers, each tends to remain closed and each is substantially free of any side thrust upon the pintle.

The sleeves used in drawers 22 and 23 are identical. The sleeve used at 280 in the fixed lower drawer 21 may be shorter and only its upper 40 end need be beveled. The sleeve 281 used in drawer 24 is shorter only because the drawer has less depth. The sleeve 282 used in the floating seal member 25 is shorter because of the lesser depth of the seal. The lower end of this sleeve also functions as a cam, being provided with a beveled surface 32 just as previously described.

When the drawers are all closed, the cam surfaces of the lower ends of the respective sleeves register with the cam surfaces 31 at the tops of the sleeve therebeneath so that the sleeves lap each other slightly as shown between sleeve 280 and sleeve 28 of drawers 21 and 22 in Fig. 5 and sleeves 281 and 282 of drawer 24 and the floating seal member 25 in the same view. However, when any drawer is opened, its initial opening movement causes the cam surface 32 at the lower end of its sleeve to react with the underlying surface 31 of the sleeve therebeneath to raise the moving drawer out of contact with the drawer beneath it. At the same time, the cam surface 31 at the upper end of the sleeve of the moving drawer interacts with the cam surface 32 of the sleeve next above it to lift the superimposed sleeve and all sleeves thereabove so that the moving drawer is also freed from marginal sliding contact with anything above it. During the continued swinging movement of the open drawer either toward its full open position or toward its closed position, the swinging drawer remains wholly out of contact with any other surface of the cabinet, pivoting upon the bearing between its sleeve and the shaft or post 16 and being 75

supported by the respective cam surfaces out of contact with contiguous drawers.

The flattened or horizontal surfaces 33 at the top ends of the respective sleeves limit the extent of the axial displacement effected by the moving drawer so that such displacement occurs only in the initial opening or final closing movement of the drawer, the swinging of the drawer throughout the rest of its range of movement being almost frictionless.

As already indicated, the drawers are nearly or substantially in contact at their marginal edges when closed, the gap between the top drawer and the top of the cabinet being substantially closed by the floating seal member 25. The telescopic movement of the floating seal member into the hollow top 11 of the cabinet accommodates the displacement which occurs as the drawers are separated in the initial opening movement of any drawer.

In order to keep the floating seal member 25 from binding in consequence of the fact that this sleeve 282 is relatively short, I desirably provide a compression spring 34 which urges such sleeve downwardly. I may also provide the floating seal member 25 with a bridge element 35 (Fig. 8) which spans diagonally the frame of the seal element 25 and has a downwardly convex cam surface at 36 engaged by the top margin of drawer 24 when the latter is opened. In the opening movement of drawer 24, the upward camming action of the drawer on the bridge 35 will lift the rear end of the seal as the front is being lifted by the cam sleeves. The function of the bridge member is particularly useful in the closing movement of drawer 24, however, when its side margin 37 will ride beneath the bridge element as shown in Fig. 8, thereby lifting the seal 25 slightly above a horizontal position so that, in ultimately returning to horizontal, it will readily follow downwardly along the shaft or post 16 to closed position on drawer 24.

As a convenient and simple means of releaseably locking the several drawers in their closed positions, I provide the rear post 12 at the back of the cabinet with a forwardly opening vertical kerf 38 in a position to receive any one of the locking pins 39 with which the respective drawers are provided immediately beneath their bottoms, as best shown in Figs. 2 and 3. Each of these locking pins has glued or otherwise fixed to its end a short length of corner molding 40 which serves as a handle for the opening of the drawer. An outward pull on the handle 40 will retract the locking pin 39 from the kerf 38 against the compression of spring 41 which is confined between the front of the drawer and a spring seat on the locking pin 39 which may conveniently be provided by clamping the split washer 42 around the wooden pin 39 as shown in Figs. 10 and 11. A short dowel at 43 may be fixed in handle 40 and engaged in a bore 44 for the further guidance of the handle as shown in Fig. 3. The pieces of corner molding 40 which serve as handles are aligned with other lengths of corner molding at 45, 46, 47 and 48 down the lefthand corners of the several drawers and adjacent portions of the cabinet.

Due to the close proximity or complete marginal contact of the top and bottom edges of the closed drawers, dust will be substantially completely excluded from the drawers when the drawers are closed. The drawers are releaseably held in closed positions by the locking pins 39 which, in the closing movement of any drawer,

are cammed toward retracted position by engagement with the surface of the rear post 12. Not until the drawer is completely shut does the pin 39 register with kerf 38 and spring into locked position. The closed position of the drawers is desirably fixed by means of a stop inserted at 50 in a vertical kerf in the back wall 13 of the cabinet at the side thereof remote from the channel 38 in which the locking pins 39 engage. This assures alignment of the drawers in vertical registration regardless of any slight working clearance which it may be desired to provide between the drawers and the back wall.

To open any drawer, the operator need only grasp the appropriate handle 40 and pull outwardly upon it. The initial outward tug upon the handle retracts the locking dowel pin and continued pull on the handle swings the drawer open, the handle being attached to a free moving corner of the swinging drawer. As soon as 15 the drawer starts to move, it lifts itself free of the drawer beneath it and raises the drawer or drawers and filler above itself due to the engagement of the cam surfaces at the lower and upper ends of its respective sleeve 28. Thus, despite the 20 fact that its margins were initially in close, dust-excluding proximity to the margins of contiguous drawers, it is immediately relieved of all such contact and its continued movement proceeds entirely on metal bearing surfaces. These 25 surfaces are so extremely close to the center upon which the drawer pivots as to offer practically no resistance to free swinging movement of the drawer. While this offers great advantages, I do not desire to limit myself to the particular arrangement disclosed, but claim as my invention:

I claim:

1. In a cabinet having a swinging drawer and members above and below said drawer with which said drawer has margins in substantial dust-excluding proximity to the closed position of the drawer, the combination with such drawer and members, of means supporting said drawer and the members for relative vertical movement, and cam means respectively carried by the drawer and 45 said members and arranged to interact in the initial opening movement of the drawer for spacing said drawer from the respective members in the course of its opening movement.

2. In a device of the character described, the 50 combination with a cabinet provided with a corner post, of a drawer unitarily comprising a sleeve journaled and reciprocable upon said post, a member above said drawer in substantial marginal contact with said drawer in the closed position thereof, said member comprising a sleeve reciprocable upon said post, the respective sleeves having coacting cam surfaces positioned for co-acting engagement in the initial swinging of the 55 drawer from closed position in a direction to displace said member upwardly free of said drawer.

3. The device of claim 2 in which at least one of said surfaces terminates at a bearing surface substantially normal to said post whereby to limit the upward displacement of said member.

4. In a device of the character described, the combination with a pivot post, of a plurality of sleeves mounted on said post for swinging and axial movement, the respective sleeves having coacting beveled cam surfaces completely nested in one position of the respective sleeves, the swinging movement of any sleeve from said position being adapted, through said cam surfaces, to effect its axial displacement with respect to at least one sleeve adjacent thereto, and members connected with the respective sleeves and normally biased toward full engagement with each other, the movement of any member with its associated sleeve being adapted to effect clearance between such member and a member adjacent thereto in consequence of the interaction of the cam surfaces aforesaid.

5. In a cabinet comprising the combination with a base, a top and a back, of a front corner post supporting a front corner of the top from a front corner of the base, a set of sleeves rotatably and axially displaceable upon said post and having coacting terminal beveled cam surfaces normally fully nested in given positions of said sleeves, drawers unitarily connected with a plurality of said sleeves for rotative and axial movement therewith, said drawers having marginal portions in substantial contact in the aforesaid positions of said sleeves, the swinging of any drawer from its said position being adapted through the interaction of cam surfaces of the respective sleeves to space said drawer from contiguous drawers.

6. The combination set forth in claim 5 in further combination with a floating dust excluding member telescopically associated with the cabinet and provided with a sleeve having a lower terminal cam surface coacting with the upper terminal cam surface of the sleeve of the top-most drawer.

WILBERT E. SCHAUER.
